United States Patent Office.

VALMORE A. DUNN, OF WEST PERU, MAINE.

Letters Patent No. 75,395, dated March 10, 1868.

IMPROVED ANVIL-CUTTER.

The Schedule referred to in these Letters Patent and making part of the same.

TO ALL WHOM IT MAY CONCERN:

Be it known that I, VALMORE A. DUNN, of West Peru, in the county of Oxford, and State of Maine, have invented a new and improved Anvil-Cutter; and I do hereby declare that the following is a full, clear, and exact description thereof, which will enable those skilled in the art to make and use the same, reference being had to the accompanying drawings, forming part of this specification.

This invention relates to an anvil-cutter, and consists in a pair of shears, one of the jaws whereof is fixed by an arm into a block or anvil.

The shears are kept open by a spring, and the nail or other article to be cut being placed on the sharp edge of the lever, the other end thereof is struck smartly with a hammer, shearing off the head fair and square, leaving the end of the nail-rod smooth for the forging of the next nail.

The accompanying drawing represents the shears mounted on the anvil or block.

Similar letters of reference indicate corresponding parts.

A A is the block; B B, the fixed jaw, having an arm, *b*, by which it is securely set in the block. The other jaw, C, has its opposing edge sharpened, and is pivoted to *b* at *c*. A spring, D, presses up the lever-arm C', keeping the shears open to receive the nail or other material to be cut. The nail being first forged, is placed on the sharp edge of C, and a smart blow being given upon the end of the lever-arm C', operates the shears, cutting smoothly off the head of the nail, and leaving the end of the nail-rod smooth for the forging of the next nail. A stop, *d*, serves to hold the spring D to the end of the lever-arm C', and to prevent the sharp edge C from jamming too far on B. E, *e e* are the horse-shoe nails as cut by my shears.

I claim as new, and desire to secure by Letters Patent—

The improved shears, composed of the fixed arm *b* and jaw B, lever C', C, and spring D, combined and arranged in manner substantially as above set forth and described.

VALMORE A. DUNN.
